PHOTOGRAPHIC FLASH GUN

Charles E. Nerpel, Van Nuys, Calif.

Application January 27, 1951, Serial No. 13,996

Term of patent 14 years

(Cl. D61—1)

To all whom it may concern:

Be it known that I, Charles E. Nerpel, a citizen of the United States, residing at Van Nuys, county of Los Angeles, State of California, have invented a new, original, and ornamental Design for a Photographic Flash Gun, of which the following is a specification, reference being had to the accompanying drawings, forming part thereof.

Fig. 1 is a front perspective view of a photographic flash gun showing my new design;

Fig. 2 is an elevational view thereof showing the side opposite that shown in Fig. 1;

Fig. 3 is a rear elevational view;

Fig. 4 is a top view; and,

Fig. 5 is a bottom view.

The dotted lines shown in the drawing are for illustrative purposes only.

I claim:

The ornamental design for a photographic flash gun, as shown and described.

CHARLES E. NERPEL.
